FLOODLIGHT

Reuben B. Benjamin, Chicago, Ill., assignor to
 Benjamin Electric Mfg. Company, Des Plaines,
 Ill., a corporation of Illinois

Continuation of application Serial No. 452,233,
 May 14, 1930. This application May 11, 1933,
 Serial No. 670,410

25 Claims. (Cl. 240—3)

This invention relates to a lighting construction and has particular reference to floodlights.

More particularly this invention relates to floodlights giving forth a highly concentrated beam surrounded by a diffused flood of light, comprising a main reflector attached to a housing hood in which is secured a socket for supporting a lamp to extend downwardly into the reflector, and an inner reflector positioned partially about the rear of the lamp for reflecting a concentrated beam of light. The socket is adapted to be pivoted in the hood so as to adjust the position of the lamp with respect to the inner reflector. The whole construction is secured to a stationary support by a pivotally adjustable bracket.

An object of this invention is to provide a floodlight for the general lighting of a large area, such as filling stations, beaches, railroad and factory yards and the like, and simultaneously spot lighting a definite location or object which it is desired to make stand out more brightly than the surrounding area.

A further object of this invention is to provide a floodlight of the type referred to above, in which the relative position of the lamp and reflectors may be easily altered. By altering the relative position of the lamp and the reflectors, the highly concentrated beam of light may be more or less concentrated, as desired, depending upon the area or object to be particularly illuminated and the purpose of the illumination. This is accomplished in the present device by having the two reflectors fixedly secured to a hood and a socket for receiving a lamp attached to a cap member which is pivotally mounted on the hood. Thus when the cap is tilted, the position of the lamp with respect to the reflectors is altered.

A still further object of this invention is to provide a floodlight which will be durable, efficient, weatherproof and easily adjustable laterally and vertically. The lateral adjustment is accomplished by means of a bracket on which the hood is pivotally mounted. In the present construction the lead wires are completely enclosed in a wiring channel which leads from the support on which the structure is mounted to the cap positioned on top of the hood.

Further objects and advantages will be more readily apparent from the following description when taken together with the accompanying drawings, in which

Figure 1 is a central vertical cross-sectional view of a floodlight embodying the present invention, shown attached to a stationary support;

Fig. 2 is an enlarged cross-sectional view of

the pivotally mounted cap to which the socket is attached, showing the cap and socket pivoted to maintain the lamp further from the inner reflector than the position shown in Figure 1;

Fig. 3 is a vertical cross-sectional view of the cap pivoted on the housing hood and the means for attaching the socket to said cap, taken on line 3—3 of Fig. 2;

Fig. 4 is a front elevational view of the inner reflector;

Fig. 5 is a top plan view, partially in section, of the inner reflector, showing the securing ring thereon;

Fig. 6 is a top plan view, partially in section, of the main reflector; and

Fig. 7 is a detailed view of a portion of the inner reflector and the positioning flange thereon.

Referring more particularly to the drawings, the construction shown comprises a main reflector 1 and an inner reflector 2, both secured to the housing hood 3. The main reflector 1 is scoop-shaped, having a substantially flat rectangular top portion 4 rounded at the sides and rear, a rounded rear end portion 5 and substantially triangular shaped sides 6 having the apex 25 thereof adjoining the front end 7 of the top portion 4. The inner reflector 2 is substantially parabolically-shaped and is provided with shallow flutes 8.

The main reflector 1 intercepts and redirects 30 upon the entire area to be illuminated light not utilized by the inner reflector 2. While efficiently redirecting the light, the main reflector 1 also acts as a shield at angles where glare would be objectionable. The light is cut off sharply in a 35 long straight line at the top edge of the beam and while the cut-off at the back and sides near the back is close beneath the fixture, considerable diffused illumination is provided by the overhanging portion of the main reflector for 40 some distance behind the cut-off. The cut-off at the sides of the main reflector 1 is such that when the unit is mounted on a 90° corner, and turned in at 45°, no glare is experienced at any 45 distance along the sides of the 90° angle. This makes the fixture exceptionally suitable for use on corners.

The inner reflector 2 is designed to intercept an adequate quantity of light to make an object or area stand out more brightly than the surrounding area illuminated by the light reflected from the main reflector. The shallow flutes 8 are provided to avoid the striations or streaks which are present where any large irregular light source is used with a polished reflector. By adjusting 55

the inner reflector 2 with respect to the main reflector 1, which may be done during the construction of the device by altering the angle between the inner reflector 2 and the flange 12 thereof, 5 the highly concentrated beam of light from the inner reflector may be focused on any area or object within the area lighted by the main reflector 1, or, if desired, it may be focused on an area or object without the area lighted by the rays 10 from the main reflector.

The main reflector 1 is provided with an opening 9 in the top thereof with an inwardly extending flange 11 about said opening, and the inner parabolic reflector 2 is likewise provided with a 15 hole 10 in the top thereof with an inwardly extending flange about said opening 10, through which openings a lamp extends into the reflectors. A positioning flange 2a is positioned about the sides of the inner reflector 2. The two reflectors 20 are attached to the bottom of the housing hood 3, which is open at the top, by means of screws 13 extending upwardly through the flange 12 of the inner reflector 2, the flange 11 of the main reflector 1, and threading into the bottom of the 25 housing hood 3. Gaskets 14 and 15 are positioned respectively between the top of the housing hood 3 and the flange 11 and between the flange 11 and the flange 12.

A cap portion 16 is pivotally mounted on the 30 upper surface of the housing hood 3. The housing hood 3 is formed with two opposite sides extending upwardly above the remainder of the hood to form a fulcrum 17 on which the cap 16 pivots, with projecting portions 18 of the cap 16 resting 35 on the fulcrum 17. Thumb screws 19 are inserted through openings 20 in the cap 16 and thread into threaded recesses 21 in the housing hood 3, the threaded recesses 21 being positioned in the upper end of said housing hood 3 intermediate the fulcrum portions 17, so that by tightening one of 40 the thumb screws 19 and loosening the other, the cap member 13 pivots on the fulcrum 17 and is fixedly positioned at all times. If desired, the fulcrum portions may be formed on the bottom of 45 the cap 16 and pivot on the top of the hood, which would then be made flat.

A socket 22 is fixedly secured to the cap portion 16 by means of screws 23 extending upwardly through the upper section of the socket 22 and 50 threading into the projecting portions 18 of the cap 16. The socket 22 is adapted to be inserted into the housing hood 3 through the opening in the top thereof, the housing hood being made sufficiently large for this purpose. Thus the socket 55 22 may be wired and secured to the cap 16 before it is inserted in the fixture. Thus when the cap 16 is pivoted on the housing hood 3 by means of the thumb screws 19, the socket 22 attached thereto pivots with it and causes the lamp 60 supported in the socket to be moved toward or away from the inner reflector 2, and thereby affects the concentration of the beam caused by the inner reflector 2.

A novel securing means is provided for pivotally mounting the lighting fixture onto a stationary support. A securing bracket 25 having a tubular portion 26 is inserted over the top of a vertical pipe 27 with a flange portion 28 resting on top of the pipe. Set screws 29 hold the bracket 25 65 from rotating on the pipe 27. A channel member 30 is provided on the top of the securing bracket 25 for guiding the lead wires from the top of the pipe 27 to the cap 16. A cover 31 fits over the top of the channel section and is secured thereto 70 by screws 32, thus providing an enclosed channel 75

from the vertical pipe 27 to the cap 16, through which the lead wires run to the wiring terminals of the socket 22. Arms 33 and 34 extend outwardly from the housing hood 3. The arm 33 is pivotally mounted on the outer, upper portion of the bracket 25 by means of a bolt 35 extending through an opening provided therefor in the bracket 25 and through an opening in the arm 33, the bolt being held in place by a nut 36. The arm 34 is arcuate, having a radius drawn on the center of the bolt 35. An arcuate slot 37 drawn on the same center is provided in the arm 34. A bolt 38 is extended through an opening provided therefor in the bracket 25 through the slot 37 and a washer 39. A nut 40 is threaded onto the end of the bolt 38 over the washer 39. In order to pivot the lighting fixture, it is only necessary to loosen the nut 40 and move the fixture forwardly or backwardly until it is in desired position and then tighten the nut 40, and a lateral 10 and vertical adjustment may thereby be obtained with a minimum of effort.

It is a simple matter to wire and mount the fixture, which is done as follows: The tubular portion 26 of the bracket 25, which supports the 15 fixture, is inserted over the lead wires and over the end of the pipe 27 until flange 28 seats on the top of the pipe. The fixture is thus held on the end of the pipe and need not be further supported. The lead wires are connected to the socket 22 20 which is then attached to the top 16. The socket is inserted in the top of the housing hood 3 and the cap 16 attached thereto. The cover 31 is then secured to the bracket 25 and the wiring is complete. Nothing further remains to be done 25 except to aim the fixture, that is, so adjust it that the light will be pointed in the desired direction. The lateral adjustment is made by rotating the bracket 25, until it is in desired position, and tightening the screws 29. The horizontal adjustment is made by loosening the nut 40 and pivoting the fixture about the bolts 35 until the fixture is 30 properly aimed and then tightening the nut 40. The fixture will then remain in this position until 35 it is again adjusted.

It may be preferable to employ a short section 40 of asbestos wire adjacent the socket 22. When this is done, the asbestos wire may be connected to the socket and the whole fixture assembled 45 before it is mounted. Then in wiring the fixture after the bracket 25 is mounted on the pipe 27, it is only necessary to splice the short section of asbestos wire extending from the fixture to the lead wires extending through the supporting pipe. 50

This application is filed as a continuation and substitute for my application, Serial No. 452,233, filed May 14, 1930.

Further modifications will be apparent to those skilled in the art and it is desired, therefore, that 60 the invention be limited only by the prior art and the scope of the appended claims.

Having thus described my invention, what I claim and desire to secure by Letters Patent is:

1. A lighting construction comprising a 65 concave reflector open at one side for emitting a beam of light, a housing hood extending upwardly from said reflector and having a cap portion thereon, said hood being formed with two opposite sides extending above the remainder of the top thereof to form a fulcrum on which the cap portion pivots, a socket in said hood attached to said cap portion for supporting a lamp to extend downwardly into said reflector, and means for pivoting said cap portion, whereby to 70 75 80 85 90 95

adjust the position of said lamp with respect to said reflector.

2. A lighting construction comprising a concave reflector open at one side for emitting a beam of light, a housing hood extending upwardly from said reflector and having a cap portion thereon, said hood being formed with two opposite sides extending upwardly above the remainder of said hood to form a fulcrum on which the cap portion pivots, a socket in said hood attached to said cap portion for supporting a lamp to extend into said reflector, and screws in said cap portion adapted to thread into said hood for pivoting said cap portion, whereby to adjust the position of said lamp with respect to said reflector.

3. A lighting construction comprising a concave reflector open at one side for emitting a beam of light, a housing hood extending upwardly from said reflector and having a cap portion pivotally mounted thereon, said hood being formed with two opposite sides extending upwardly above the remainder of said hood to form a fulcrum on which the cap portion pivots, a socket in said hood attached to said cap portion for supporting a lamp to extend into said reflector, screws in said cap portion adapted to thread into said hood for pivoting said cap portion, a substantially parabolic reflector positioned behind said lamp and about the rear side thereof, whereby when said cap portion with the socket thereon is pivoted, the distance between the light source and the parabolic reflector may be varied.

4. The combination with a lighting construction comprising a concave reflector open at one side for emitting a beam of light, a housing hood having a cap thereon extending upwardly from said reflector and having a socket therein for supporting a lamp to extend into said reflector, of means for pivotally mounting said lighting construction comprising a securing bracket having an enclosed wiring channel thereon and mounted to a stationary support, said wiring channel extending into said cap, arms on said hood, the upper of said arms being pivotally connected to said supporting bracket and the lower of said arms having a slot therein for engaging securing means on said bracket, whereby said lighting fixture may be laterally pivoted and then maintained in desired position.

5. A lighting construction comprising a lighting fixture having a concave reflector, a housing hood with a cap thereon extending upwardly from said reflector and having a lamp receptacle therefor for supporting a lamp to extend into said reflector, and means for adjustably mounting said lighting fixture comprising a securing bracket pivotally attached to said lighting fixture and having a socket portion adapted to fit over the end of an upright supporting member whereby to hold said lighting fixture in desired position on said upright supporting member, said securing bracket having a wiring channel therein for conducting the lead wires from said upright supporting member to said lighting fixture and a cover for said wiring channel extending into said cap.

6. A lighting construction comprising a reflector, a housing hood extending upwardly therefrom, a member rockably mounted adjacent the upper end of said hood, said hood having portions for supporting opposite sides of said member whereby it may be rocked on said hood, and a socket in said hood attached to said rockably mounted member for supporting a lamp to ex-

tend downwardly into said reflector, whereby when said member is rocked, the position of said lamp with respect to said reflector is altered.

7. A lighting construction comprising a concave reflector open at one side for emitting a beam of light, a housing hood extending upwardly from said reflector, a cap portion rockably mounted on said hood, said hood having portions for supporting opposite sides of said cap whereby said cap may be rocked on said hood, and a socket in said hood attached to said cap portion for supporting a lamp to extend downwardly into said reflector whereby when said cap is rocked, the position of said lamp with respect to said reflector is altered.

8. A lighting construction comprising a concave reflector open at one side for emitting a beam of light, a housing hood extending upwardly from said reflector, a cap portion rockably mounted on said hood, said hood having portions for supporting opposite sides of said cap whereby said cap may be rocked on said hood, a socket in said hood attached to said cap portion for supporting a lamp to extend downwardly into said reflector, and means for rocking said cap portion whereby to adjust the position of said lamp with respect to said reflector.

9. A lighting construction comprising a concave reflector open at one side for emitting a beam of light, a housing hood extending upwardly from said reflector, a cap portion rockably mounted on said hood, said hood having portions for supporting opposite sides of said cap whereby said cap may be rocked on said hood, a socket in said hood attached to said cap portion for supporting a lamp to extend downwardly into said reflector whereby when said cap is rocked, the position of said lamp with respect to said reflector is altered, and means for maintaining said cap portion in desired position.

10. A lighting construction comprising a concave reflector for flood-lighting a large area, a hood extending upwardly from said reflector, a cap portion rockably mounted on said hood, said hood having portions for supporting opposite sides of said cap whereby said cap may be rocked on said hood, a socket in said hood attached to said cap portion for supporting a lamp to extend downwardly into said reflector, and a concave parabolic reflector positioned at the rear of said lamp for spot-lighting a portion of the flood-lighted area whereby when said cap is rocked, the distance between the light source and the parabolic reflector is varied.

11. A weatherproof lighting unit comprising a casing for a light projecting construction, a hood extending upwardly from said casing and having an open upper end, a cover extending across and covering said opening and having a skirt portion overhanging the periphery of the hood, a lamp socket mounted on said cover for supporting the lamp bulb within the casing, and means for mounting said cover for rocking movement on the hood on a fixed axis to vary the position of the light source within the casing.

12. A weatherproof floodlighting construction comprising a drainage-excluding hood covered at the top and open at the bottom, a drainage-excluding reflector housing below and secured to the lower edge of the hood and sloping downwardly and forwardly from the hood, a socket in the hood for supporting a lamp with its light source in said housing, said reflector housing having a diffusing reflector surface arranged to direct diffused light over a large field, a polished re-

5 reflector in said housing in the rear of the lamp for reflecting a beam of light in the field of the diffused light and over a restricted field, said socket being adjustable for focusing the lamp substantially on the axial line of the polished reflector for varying the restricted beam of light, the rear portion of the housing closely surrounding said polished reflector and the lower edge of the housing lying adjacent and back of the 10 lower edge of the polished reflector.

13. A combined weatherproof flood and spot-light construction comprising an inverted concave diffusing reflector, a tubular hood extending upwardly from said reflector and open at both 15 ends, a removable weatherproof socket-supporting cap on said hood, a socket secured to said cap and extending into said hood to hold a lamp with its light source in said diffusing reflector, a polished spotlight reflector in said diffusing reflector and closely adjacent said lamp and arranged to direct a concentrated spotlight beam, and means for tilting said cover to vary the concentration of said spotlight beam.

14. A combined weatherproof flood and spot-light construction comprising an inverted concave diffusing reflector, a tubular hood extending upwardly from said reflector and open at both ends, a removable weatherproof socket-supporting cap on said hood, a socket secured to said 25 cap and extending into said hood to hold a lamp with its light source in said diffusing reflector, a polished spotlight reflector in said diffusing reflector and closely adjacent said lamp and arranged to direct a concentrated spotlight beam, 30 and means for tilting said cover to vary the concentration of said spotlight beam and arranged to simultaneously secure said cover in adjusted position.

15. An outdoor floodlighting construction, 40 comprising a lamp receptacle for supporting a lamp in depending position with its axis substantially vertical, a hood surrounding and housing said receptacle, and a reflector supported by said hood in depending position so that the lamp extends from said hood downwardly into said reflector, said reflector having an upper substantially flat diffusing reflecting surface for reflecting all of the rays falling thereon forwardly and downwardly to form part of the diffused 45 floodlighting beam extending downwardly and forwardly to a front cut-off edge, a rear reflecting surface concave both in vertical and lateral extending downwardly to a lower rear cut-off edge for directing a beam of light forwardly and 50 downwardly and side diffusing reflector surfaces extending between said front and rear reflector surfaces, the upper cut-off edge being materially farther from the light source than is the rear cut-off edge, said lower rear cut-off edge being 55 positioned to enable direct downward illumination adjacent the axis of the lamp, and said reflector having its upper reflecting surface and its side reflecting surfaces of light-diffusing characteristics and having its rear reflecting surface of 60 non-diffusing characteristics, and means whereby the light source may be adjusted toward and from the rear reflecting surface to vary the spread of the beam from the rear reflecting surface.

16. A floodlighting construction comprising a 70 lamp receptacle for supporting a lamp in depending position with its axis substantially vertical, a hood surrounding and housing said receptacle, and reflector means supported by said hood in depending position so that the lamp extends 75 from said hood downwardly into said reflecting

means, said reflecting means including an upper substantially flat reflecting surface extending downwardly and forwardly from the hood and terminating in a substantially horizontal front cut-off edge, a rear concave bowl-like beam-reflecting surface, concave both in vertical and lateral planes and having its axis approximately parallel to the plane of said upper flat reflecting surface whereby said upper surface does not interfere materially with the beam from the bowl-like reflector surface and whereby the beam can be projected a long distance forwardly from the axis of the lamp, and side reflecting surfaces extending between said upper flat reflecting surface and said bowl-like reflecting surface. 10

17. A floodlighting construction comprising a lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means including an upper substantially flat reflecting surface extending downwardly and forwardly from the hood and terminating in a substantially horizontal front cut-off edge, a rear concave bowl-like beam-reflecting surface, concave both in vertical and lateral planes and having its axis approximately parallel to the plane of said upper flat reflecting surface 20 whereby said upper surface does not interfere materially with the beam from the bowl-like reflector surface and whereby the beam can be projected a long distance forwardly from the axis of the lamp, and side reflecting surfaces extending between said upper flat reflecting surface and said bowl-like reflecting surface, said reflecting means having its upper reflecting surface and its side reflecting surfaces of light diffusing characteristics and having its rear bowl-like beam-reflecting surface of non-diffusing characteristics. 30

18. A floodlighting construction comprising a lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means including an upper substantially flat reflecting surface extending downwardly and forwardly from the hood and terminating in a substantially horizontal front cut-off edge, a rear concave bowl-like beam-reflecting surface, concave both in vertical and lateral planes and having its axis approximately parallel to the plane of said upper flat reflecting surface whereby said upper surface does not interfere materially with the beam from the bowl-like reflector surface and whereby the beam can be projected a long distance forwardly from the axis of the lamp, and side reflecting surfaces extending between said upper flat reflecting surface and said bowl-like reflecting surface, said reflecting means having its upper reflecting surface and its side reflecting surfaces of light diffusing characteristics and having its rear bowl-like beam reflecting surface of non-diffusing characteristics, said lighting construction including a housing member for the bulb on which said upper and side reflecting surfaces are formed 50 and a bowl-like member on which said rear reflecting surface is formed, the rear portion of said housing member embracing and conforming in general to the shape of said bowl-like member. 60

19. A floodlighting construction comprising a 75

lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means including an upper substantially flat reflecting surface extending downwardly and forwardly from the hood and terminating in a substantially horizontal front cut-off edge, a rear concave bowl-like beam-reflecting surface, concave both in vertical and lateral planes and having its axis approximately parallel to the plane of said upper flat reflecting surface whereby said upper surface does not interfere materially with the beam from the bowl-like reflector surface and whereby the beam can be projected a long distance forwardly from the axis of the lamp, and side reflecting surfaces extending between said upper flat reflecting surface and said bowl-like reflecting surface, said reflecting means having its upper reflecting surface and its side reflecting surfaces of light diffusing characteristics and having its rear bowl-like beam reflecting surface of non-diffusing characteristics, said lighting construction including a housing member for the bulb on which said upper and side reflecting surfaces are formed and a bowl-like member on which said rear reflecting surface is formed, the rear portion of said housing member embracing and conforming in general to the shape of said bowl-like member, said bowl-like member being provided with a securing flange surrounding the neck of the bulb.

20. A floodlighting construction comprising a lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means including an upper substantially flat reflecting surface extending downwardly and forwardly from the hood and terminating in a substantially horizontal front cut-off edge, a rear concave bowl-like beam-reflecting surface, concave both in vertical and lateral planes and having its axis approximately parallel to the plane of said upper flat reflecting surface whereby said upper surface does not interfere materially with the beam from the bowl-like reflector surface and whereby the beam can be projected a long distance forwardly from the axis of the lamp, side reflecting surfaces extending between said upper flat reflecting surface and said bowl-like reflecting surface, and means whereby the light source may be adjusted toward and from the rear reflecting surface to vary the spread of the beam from the rear reflecting surface.

21. A floodlighting construction comprising a lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means having a rear concave bowl-like beam-reflecting surface, concave both in vertical and lateral planes, and having its axis extending downwardly and forwardly substantially through the center of the light source, and a front reflecting surface lying substantially in front of the axis of the lamp receptacle having its uppermost portion extending in a substantially

a substantially straight line substantially parallel to the axis of the rear bowl-like beam-reflecting surface downwardly and forwardly from the hood to a front cut-off edge, whereby the beam from the bowl-like reflecting surface can be projected a long distance forwardly from the axis of the lamp, said front reflecting surface embracing the beam from the rear reflecting surface and being spaced from the axis of the beam far enough so as not to interfere therewith.

22. A floodlighting construction comprising a lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means having a rear concave bowl-like beam-reflecting surface, concave both in vertical and lateral planes, and having its axis extending downwardly and forwardly substantially through the center of the light source, and a front reflecting surface lying substantially in front of the axis of the lamp receptacle having its uppermost portion extending in a substantially straight line substantially parallel to the axis of the rear bowl-like beam-reflecting surface downwardly and forwardly from the hood to a front cut-off edge, whereby the beam from the bowl-like reflecting surface can be projected a long distance forwardly from the axis of the lamp, said front reflecting surface embracing the beam from the rear reflecting surface and being spaced from the axis of the beam far enough so as not to interfere therewith and having a light-emitting opening lying substantially in a plane extending forwardly and upwardly from the lower edge of the rear bowl-like beam-reflecting surface to said cut-off edge.

23. A floodlighting construction comprising a lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means having a rear concave bowl-like beam-reflecting surface, concave both in vertical and lateral planes, and having its axis extending downwardly and forwardly substantially through the center of the light source, and a front reflecting surface lying substantially in front of the axis of the lamp receptacle having its uppermost portion extending in a substantially straight line substantially parallel to the axis of the rear bowl-like beam-reflecting surface downwardly and forwardly from the hood to a front cut-off edge, whereby the beam from the bowl-like reflecting surface can be projected a long distance forwardly from the axis of the lamp, said front reflecting surface embracing the beam from the rear reflecting surface and being spaced from the axis of the beam far enough so as not to interfere therewith, said lighting construction including a housing member for the bulb on which said front reflecting surface is formed, and a bowl-like member on which said rear reflecting surface is formed, the rear portion of said housing member embracing and conforming in general to the shape of said bowl-like member.

24. A floodlighting construction comprising a lamp receptacle for supporting a lamp in depending position with its axis substantially vertical, a hood surrounding and housing said receptacle, reflector means supported by said hood in

depending position so that the lamp extends from said hood downwardly into said reflecting means, said reflecting means having a rear concave bowl-like beam-reflecting surface, concave both in vertical and lateral planes, and having its axis extending downwardly and forwardly substantially through the center of the light source, and a front reflecting surface lying substantially in front of the axis of the lamp receptacle having its uppermost portion extending in a substantially straight line substantially parallel to the axis of the rear bowl-like beam-reflecting surface downwardly and forwardly from the hood to a front cut-off edge, whereby the beam from the bowl-like reflecting surface can be projected a long distance forwardly from the axis of the lamp, said front reflecting surface embracing the beam from the rear reflecting surface and being spaced from the axis of the beam far enough so as not to interfere therewith, and means whereby the light source may be adjusted toward and from the rear reflecting surface to vary the spread of the beam from the rear reflecting surface.

25. A floodlighting construction comprising a lamp receptacle for supporting a lamp in depending position with its axis substantially vertical, a hood surrounding and housing said receptacle, and reflector means supported by said hood in depending position so that the lamp extends from said hood downwardly into said reflecting means, said reflecting means including an upper substantially flat reflecting surface extending downwardly and forwardly from the hood and terminating in a substantially horizontal front cut-off edge, a rear concave beam-reflecting surface for reflecting a beam, the axis of which beam extends substantially parallel to the plane of said upper flat reflecting surface, whereby said upper surface does not interfere materially with the beam from the rear reflector surface and whereby the beam can be projected a long distance forwardly from the axis of the lamp, and side reflecting surfaces extending between said upper flat reflecting surface and said rear reflecting surface. 5 10 15 20

REUBEN B. BENJAMIN.

CERTIFICATE OF CORRECTION.

Patent No. 2,040,821.

May 19, 1936,

REUBEN B. BENJAMIN.

It is hereby certified that error appears in the printed specification of the above numbered patent requiring correction as follows: Page 4, first column, line 52, claim 15, after the word "lateral" insert planes; and that the said Letters Patent should be read with this correction therein that the same may conform to the record of the case in the Patent Office.

Signed and sealed this 28th of July, A. D. 1936.

(Seal)

Henry Van Arsdale
Acting Commissioner of Patents.
